Primary Examiner—Alan P. Douglas*Assistant Examiner*—Antoine D. Davis*Attorney, Agent, or Firm*—Pearne, Gordon, McCoy & Granger**[57] CLAIM**

The ornamental design for a suspension instrument for rotor of grinding machine, as shown and described.

DESCRIPTION

FIG. 1 is a top plan view of a suspension instrument for rotor of grinding machine showing our new design;

FIG. 2 is a bottom plan view;

FIG. 3 is a front elevational view;

FIG. 4 is a rear elevational view;

FIG. 5 is a right side elevational view;

FIG. 6 is a left side elevational view; and,

FIG. 7 is a perspective view thereof.
